US0D1002130S

(12) **United States Design Patent** (10) **Patent No.:** **US D1,002,130 S**
(45) **Date of Patent:** **** Oct. 17, 2023**

(54) **WASHING MACHINE**

(71) Applicant: **Guangzhou EZVALO Technology Co., Ltd.**, Guangzhou (CN)

(72) Inventors: **Wuxu Liu**, Guangzhou (CN); **Zhuowen He**, Guangzhou (CN)

(73) Assignee: **GUANGZHOU EZVALO TECHNOLOGY CO., LTD.**, Guangzhou (CN)

(**) Term: **15 Years**

(21) Appl. No.: **29/803,099**

(22) Filed: **Aug. 10, 2021**

(30) **Foreign Application Priority Data**

Feb. 26, 2021 (CN) 202130108843.4
